ABSTRACT OF THE DISCLOSURE

An improved ionization source for a mass spectrometer which sources employ a tip array anode consisting of a multiplicity of individual anode tips arrayed on a support means. The anodes contemplated may consist of a row of evenly spaced tips or alternatively there may be two or more such rows.

FIELD OF THE INVENTION

This invention relates to mass spectrometry and to means and methods for increasing the sensitivity of a mass spectrometer. More particularly, the invention relates to the use of field ionization in mass spectrometers and is specifically concerned with improved field-ionization anodes.

Mass spectrometry is one method of determining the chemical or elemental composition of a material. In the conventional mass spectrometer, the material to be examined is introduced into an ionization chamber and subjected to electron bombardment which causes the material to ionize. The ions thus generated are accelerated in a mass tube by an electrostatic field and are resolved into successive groups of individual mass by the dispersing power of a magnetic field. The relative abundance of each mass group is then measured and recorded in peaks on an oscillographic chart. Every ionized mass group has a distinct mass-to-charge (m/e) ratio and, therefore, should appear as a separate peak on the oscillographic record.

The present invention is directed to providing an improved apparatus and method of mass spectrometry. In contrast to the more conventional spectrometers which use electron bombardment for providing an ion source, the instant invention relates in particular to improvements in those spectrometers which make use of a field ionization source. Field ionization is a preferred kind of mass spectrometry which lead to simpler spectra. In this process, the sample of material to be analyzed is vaporized and the vaporized molecules are allowed to pass into a region of very high electrostatic field strength between an anode and a cathode which are about 2 mm. apart. In the region between the anode and the cathode an electrostatic field gradient on the order of about 10^8 volts per centimeter is generated. This field gradient results in a stress which is sufficient to abstract an electron from a molecule. As a result a positive ion is formed and this ion is then quickly ejected from the region of high stress by the repulsion of the field-ion anode. From this point the mixture of ions is analyzed by any of the conventional mass spectrometric methods known to those skilled in the art. The field ionization technique yields a greater abundance of parent ions and lesser amounts of fragment ions as compared to the electron bombardment techniques and, hence, is of greater advantage in the analysis of mixtures of molecules.

The large field gradient of about 10^8 volts per centimeter referred to above may be established by using an

2

anode possessing a very small radius of curvature. For example, it may be calculated that a field-ion anode in the form of a thin wire having a diameter of 0.25 micro can create a field stress of 76×10^6 volts per centimeter near the surface of the wire, while using a potential difference between the thin wire anode and cathode of 10,000 volts.

In the past three basic types of field-ionization anodes have been used in mass spectrometers. The first of these is in the form of an individual small radius tip made of some refractory material such as tungsten, platinum or gold, the radius of curvature of the tip being about 50 to 1000 angstroms and being obtained by electrolytical etching the tip. Most of the published literature in this field is based on such a tip anode. The second type makes use of a razor blade as an anode; however, the use of this type anode has been restricted because of limitations of the field stress which may be applied to the blade. The third type uses the small diameter wire referred to above. It should be appreciated that these fine anode wires known in the art as Beckey-Wollaston wires, are very fragile and difficult to make and to use. Off-setting these disadvantages in the past has been the fact that sensitivities using such wire anodes could be 100 to 1000 times greater than those obtained with single anode tips. A further limitation is imposed on the use of each of the prior art anodes in that they can not take advantage of the angular dependence of ion abundances which come from the tip of the source in order to increase signal strength, as may the anode of the instant invention, as will be discussed hereinafter. Thus, a specific purpose of the instant application is to provide a more durable and practical device which produces a stronger signal to serve as the field-ionization anode. This device will be referred to as a tip array anode.

SUMMARY OF THE INVENTION

The improved anode of the instant invention comprise a multiplicity of individual anode tips side by side and mounted on a horizontal support rod. The individual wires before they are sharpened by electrolytic etching may be 0.010 to 0.025 mm. in diameter and their spacings may be in the range of from about 2 mm. to 10 mm. between individual wires. The tip-array anodes of the instant invention may consist of one such row of evenly spaced tips or alternatively may be of two such rows in parallel or several such rows. In the latter case the device will be referred to as a "pin cushion" array. While certain arrays have been used in the past in X-ray tubes and electron microscopes, their function therein has been that of a field-emitter. At this point it is important to distinguish between field-emission and field-ionization. A field-emitter is a cathode capable of providing a very high density negative electrical discharge. Field ionization, as hereinbefore discussed, is a newer development and uses reverse electrical polarity so that the small radius device is an anode in this case. Thus, the instant invention is directed to the application of a tip array device as a practical anode in the field ionization mass spectrometer source.

Thus, an object of the invention is to provide a tip array anode for use in a field ionization mass spectrometer source.

Another object of the invention is to provide a more durable anode with capabilities for greater sensitivities than can be obtained with the anodes of the prior art.

Yet another object is to provide an anode which, because of the way it forms ions, yields a greater abundance of desired primary metastable ions relative to the abundance of parent ions than is obtainable with the presently used anodes of the art.

Still another object of the instant invention is to provide an anode which can take advantage of the angular

endence of the ion abundances which come from the rce in order to increase signal strength. These and further objects as well as a fuller understanding of the invention may be had by reference to the ompanying detailed descriptions and by referring to drawings in which:

BRIEF DESCRIPTION OF THE DRAWINGS

FIG. 1 is a simplified schematic illustration of a conventional mass spectrometer incorporating the improved ide of the instant invention.

FIG. 2 is an enlarged view of the area enclosed by dotted line in FIG. 1.

FIGS. 3A, 3B and 3C depict preferred configurations of the improved anode of the instant invention.

FIG. 4 is a graph depicting the angular dependency of rgy coming from a single field-ionization anode.

FIG. 5 depicts schematically the energy "cones" emerging from the tips of a plurality of anode tips.

FIG. 6 indicates schematically the preferred orientation of the tip-array anode with respect to the slit in the node.

DESCRIPTION OF PREFERRED EMBODIMENTS

Referring now to the figures in detail and particularly FIG. 1, a schematic diagram of a simplified mass spectrometer employing the improvement of the instant invention is shown. That portion of FIG. 1 not enclosed within dotted lines operates in a conventional manner. It is comprised of a mass spectrometer tube 10 provided with ionization end 11, a magnet 12, and an ion collector or detector end 16. An ionization head generally indicated at 13 is affixed to the ionization end 11 of mass spectrometer tube 10. The operations of head 13 will be discussed in greater detail in conjunction with the discussion of FIG. 2.

In operation, the material to be analyzed is admitted to the ionization head 13 by means of a suitable inlet. There the sample is ionized and the ions produced in head are expelled from the ionization chamber into tube 10. As the ionized particles travel through the ss tube 10, they are resolved into separate homogenous beams such as 15, 17 and 19 by means of a mag- field produced between the poles of the electro- magnet 12. The strength of the magnetic field in magnet 12 may be controlled and is a function of the current flowing through the winding 14. At any given strength of imposed magnetic field, only that homogenous ion beam, e.g. beam 17, whose mass-to-charge ratio (m/e) responds to the strength of the magnetic field can negotiate the curved section of the mass tube and pass through the collector slit 21. The ions passing through the collector slit impinge on a collecting electrode (not shown) within the detector head 16 and produce a small current. This current is amplified and recorded by means of a suitable apparatus 18. An oscillographic chart (not shown) produced by the recording apparatus 18 indicates the extent of resolution.

Referring now to FIG. 2, an enlarged view of the ionization head 13 of FIG. 1 is shown. The head 13 may be conveniently referred to as a dual field-ionization and electron impact source. In this regard head 13 consists of an upper portion 6 and a lower portion 8, portion 6 containing what shall be designated as a tip array field ionization source while portion 8 contains an electron-impact source of ions of the conventional type which is known in the art as a Nier-type source. Referring further to the tip array field ionization source contained in portion 6 of head 13, an anode support rod 26 is maintained in position in the upper part of portion 6 by the insulated connector 24. At its distal end, support rod 26 carries an anode holding member 28, which is secured to rod 26 by means of the set-screw 30. In a preferred embodiment, holding member 28 may have its lower portion 31 rotatably mounted on its upper portion 29, so that the included angle between these portions may be adjusted.

The significance of this arrangement will be discussed hereinafter. The lower portion of anode holder 28 supports a tip-array anode generally indicated at 35, which is comprised of a multiplicity of individual anode tips 34, which are mounted side-by-side on a tip support rod 32.

5 The individual wires comprising the said multiplicity of anode tips may be from 0.0100 to 0.0250 mm. in diameter (before electrolytic etching) and their spacings may be in the range of 2 to 10 mm. between the individual wires. 10 As previously indicated, a tip-array anode may consist of one such row of evenly spaced tips or alternatively there may be two such rows in parallel or several such rows. Preferred configurations of such tip-array anodes will be discussed in further detail pursuant to the discussion of FIG. 3.

15 Positioned below tip-array anode 35 is a cup-shaped cathode 36, defining in its bottom portion a slit 41. Through the use of a suitable control means 5, cathode 35 may be maintained at a negative potential in the range of -500 to -10,000 volts by the lead 9. It is to be appreciated that the cathode is carefully insulated from the walls of head 13. Similarly, the potential of the tip-array anode may be suitably controlled within the range of +1000 to +12,000 volts by use of positive voltage control 7 connected to holder 28 by lead 43. With the tip-array anode having a potential of +3000 volts and with the cathode potential set at -7000 volts, it can be calculated that each one of the individual ion anode wires comprising the tip-array can create a field stress of approximately 73×10^6 volts per centimeter near the surface of the wire. This stress is sufficient to abstract an electron from a molecule of the sample entering the head through the inlet line 4. As a result, a positive ion is formed and this is quickly ejected from the region of high stress by the repulsion of the field-ion anode. A multiplicity of ions so formed will thus emerge from the slit 41 in the cathode 36. This beam then passes through the slot 58 of the box 42 of a conventional electron-impact source. With the tip-array anode in use, box 42 provided with tap terminal 56 may be maintained in the voltage range of 0 to +2000 volts and preferably in the range of +100 to +200 volts by the variable resistor 47 which is connected via the lead 45 to control 7. The ion beam then continues through the box 42 and passes through the slit 66 located in the bottom thereof. It then enters a slit 69 defined by a pair of drawout plates 68 and 70. For purposes of discussion these plates will be designated with respect to their relative position as indicated in FIG. 1; that is, plate 70 will be referred to as the upper drawout plate and plate 68 shall be designated as the lower drawout plate. Each of these plates is provided with a separate terminal 72 and 74 respectively, so that each plate may be maintained at a different potential by the use of resistor 47 and control 7. The function of this pair of plates is to straighten out the beam as it passes between them. Thus, for example, if the beam was following the curvilinear path indicated by the dotted arrow *a* in FIG. 2 as it approached the plates 68 and 70, its path could be made to follow the arrow *b* by suitably adjusting the potentials on plates 70 and 68. In the preferred embodiment the upper plate may be maintained at a voltage in the range of 1400 to 1500 volts. The lower plate may be maintained at a potential of about 400-500 volts less. However, it is to be appreciated that the difference in voltage between these two plates will be subject to continuing adjustments so as to translate any curvilinear motion of the beam into rectilinear motion as the beam passes through slit 66 between the two plates. The ion beam then passes through the slit defined by the plates 78 and 80, which may also be maintained at different potentials by resistor 47. This pair of plates functions in a similar manner to plates 68 and 70 and may be represented as providing fine tuning for the focusing of the beam, whereas plates 68 and 70 provide the initial adjust-

ment. These plates may be maintained in a lower voltage range, for example, 100 to 200 volts and the voltage difference between them may be in the range of 50 to 150 volts, which difference is also subject to adjustment to provide the required focusing. The straightened beam then passes through the slit defined by the plates 88 and 90. These plates are usually maintained at 0 voltage. It will be appreciated that the pairs of plates previously described serve to adjust the path of the beam in the plane of FIG. 2. Adjustment of the direction of the beam in a plane perpendicular to that of the figure is accomplished by means of the plates 92 and 94, which may be maintained with a suitable voltage difference so as to center the beam in the middle of tube 10.

While the ionization head 13 may be equipped solely with the tip-array anode device discussed in the above paragraphs, it may also be conveniently equipped with an electron-impact source of the conventional Nier type. This gives a somewhat extended flexibility of operation in the analysis of molecules which vary in their ability to be ionized. The workings of the Nier-type electron-impact source may be conveniently understood by once again referring to FIG. 2.

A current is passed from the filament controller 3 through the filament 50 via the terminals 52 and 54. This flow of current causes the filament to emit a steady stream of electrons. The material to be analyzed is introduced through the inlet 4 and works its way down into box 42. There the sample is subjected to the electron beam C emitted from the filament 50. As the electrons of beam C impinge upon the molecules of the sample, ions are formed. These ions which are, of course, positively charged particles are ejected from the box 42 and through the slots defined by the various pairs of plates 68 and 70, 78 and 80, and 90 and 88. To insure that the electron beam follows substantially the path indicated by the dotted line C, a collector plate 62 provided with a terminal tap 64 is maintained at a voltage supplied by control 7 through the lead 51, which is more positive than that of the filament or the walls of the chamber 42. Thus, in a typical application the filament would be maintained at a voltage of approximately +2930 volts. The walls of the box 42 would be maintained at a voltage of approximately +3000 volts and the electron collector 62 would have a voltage in the range of +3080 volts. When the electron-impact source is in use, the pairs of plates located under box 42 would function in much the same manner as previously described; however, they would be operated in somewhat different voltage ranges. Thus, plates 68 and 70 would be operated in the range of 2000 to 3000 volts, whereas plates 78 and 80 would be operated in the range of about 150 to 300 volts.

Reference will now be had to FIG. 3 to illustrate three of the preferred embodiments for the improved tip-array anode of the instant invention. FIG. 3(A) represents a single row tip-array anode. As may be seen, it consists of a multiplicity of individual small diameter wires 34 which are arranged side-by-side on a support rod 32 and in good electrical contact therewith. The individual wires preferably have diameters in the range of 0.0100 to 0.025 mm. and each wire has a tip which has a radius of curvature preferably in the range of about 500 to 1000 angstroms, this radius being obtained by electrolytically etching the wires. The spacings between the individual wires are preferably in the range of 0.0005 mm. to 0.0025 mm. Another form of the tip-array anode is indicated in FIG. 3(B). The anode of FIG. 3(B) is similar in construction to that of FIG. 3(A) except that a double row of individual wires is provided. These rows are designated e and f in FIG. 3(B). Still another preferred form of the tip-array anode is depicted in FIG. 3(C). This has previously been referred to as the "pin cushion" configuration and it consists of a multiplicity of rows of individual wires 34 which are maintained in position by a conductive block 37 in which the wires are embedded.

Experiments to be herein subsequently discussed were conducted using tip arrays which were fabricated from tungsten. However, in this regard it is to be appreciated that inert materials such as gold, platinum, iridium rhodium, and rhenium are particularly suitable for fabricating these anodes.

A particular advantage of the anode of the instant invention is its durability as compared to the devices of the prior art. The Beckey-Wollaston wires hereinbefore discussed of the usual 2.5 micron diameter are extremely fragile and are susceptible to breakage even due to slight jolts during handling. Their use over any period of time depends on following the most exact operating procedure and allows very little room for deviation. By comparison a tip array of the type herein described and shown in FIG. 3B was used under a wide variety of conditions over a period of 48 days with no problems. In addition it has experimentally been established that the tip-array anodes of the instant invention can deliver a larger signal than one can obtain using a Beckey-Wollaston wire or an individual anode tip in the same mass spectrometer source. In this regard reference should be had to the first two entries in Table I below, which presents the sensitivity of acetone in chart divisions of an oscilloscopic readout chart per micromole of acetone using Beckey-Wollaston wire and using a tip-array anode of the type depicted in FIG. 3B. It may be seen that the sensitivity has been increased by approximately 39%.

TABLE I

Type of field-ion anode:	Sensitivity of acetone
(1) Beckey-Wollaston wire	39,000 chart division per micromole.
(2) Tip-array (Type 3B) mounted vertically and parallel to cathode slit	54,000 chart division per micromole.
(3) Tip-array (Type 3B) mounted parallel to cathode slit but at 40° to vertical	82,000 chart division per micromole.

A comparison of entries 2 and 3 leads to the discussion of yet another improvement which may be achieved utilizing the teachings of the instant invention. It has been shown in the prior art that the energy coming from a single field ionization anode; that is, the pattern of positive ion density has an angular dependency. As the electrostatic field stress is increased (as previously indicated this is a function of the potential difference between the anode and the cathode) there is an increase in the total number of positive ions. In addition, with increasing field stress the locus of the energy distribution of these ions emerging from the tip becomes the surface of a solid cone. As the field stress becomes greater, the internal angle of this cone becomes larger until it maximizes at a given angle for a given field stress. This angular dependency is depicted in the graph of FIG. 4. Thus, it may be seen, for example, that with a potential between the anode and the cathode of 16,000 volts, the greatest possible ion density will be defined by a cone having an apex angle of 80°; that is, when viewed in cross-section the sides of the cone will form an angle of 40° with the line which defines the direction of the individual wire anode. If one now arranges many such tips in a double row configuration as shown in FIG. 5 (this represents the specific embodiment of the anode of FIG. 3B), one should expect a certain circle of confusion in the field between each of the rows of individual anode tips where the cones intersect. Also, the net result will be a maximization of energy in the planes designated HLJK and LMP of FIG. 5. Thus, the geometry indicates that the locus of maximum energy will be in the range of about 40°-50° from the vertical under the conditions above

d. The configurations of the anodes depicted in GS. 3A and 3B allow this angular energy distribution be effectively utilized. Thus, if the anode of the instant invention is located with respect to the slit in the cathode as diagrammatically indicated in FIG. 6, an improvement in the signal strength may be achieved. The result may be demonstrated by referring to the second and third entries in Table I above. Thus, as indicated in entry 2 where the tip array was mounted vertically and parallel to the slit in cathode 41, the sensitivity of acetone was 10 assurred at 54,000 chart divisions/micromole. However, when the tip array was mounted at 40° to the vertical, indicated in FIG. 6, and still being parallel to the slit in cathode 41, an increase of approximately 52% the sensitivity was achieved. This finding demonstrates 15 the referred way in which these tip arrays may be oriented with respect to the cathode slit to yield increased signal strength. It also teaches that the mounting angle of the array should be correlated with the operating conditions of the source; that is, the potential difference existing between the cathode and the anode. By having the outer portion of holder 28 pivotably mounted on the inner portion 29 as hereinbefore recited, the mounting angle of the tip array may be easily adjusted to produce 20 maximal strength.

Still another advantage of the instant invention is that it can make better use of metastable ions for purposes of molecular structure determinations. This may be explained by the fact that field ionization of the type herein described may be considered to be a more "gentle" way of forming ions. That is to say that the individual molecules of the sample will be less subject to increases in fragmentation where an electron is withdrawn by the use of field ion anodes, than will be the case where the molecule is bombarded by a stream of electrons. It has been established that the tip-array anodes of the instant invention will deliver a greater abundance of metastable ions relative to the abundance of the parent ions than will a single anode of the Beckey-Wollaston type. This may be 30 shown by comparison of entries 1 and 2 in Table II. There is indicated that starting with a sample of n-octane, which produces a parent ion having a mass-to-charge ratio of 114, more of the metastable ion having a mass-to-charge ratio of 63.38 will be produced using the tip array than will be produced using the Beckey-Wollaston wire. 35

TABLE II

Type of field-ion anode	Abundances of ions in n-octane	
	Parent ion (m/e)=114	Metastable ion (m/e)=63.38
Beckey-Wollaston wire-----	100.0	11.2
Tip-array anode (type 3B)-----	100.0	15.4

Although the foregoing invention has been described in some detail by way of illustration and example for purposes of clarity and understanding, it should be understood that certain changes and modifications may be practiced within the spirit of the invention as limited only by the scope of the following appended claims:

What is claimed is:

1. In a mass spectrometer an improved field ionization source which comprises in combination:
  - a) a first member comprising a cathode;
  - b) an anode holder having first and second portions arranged in seriatum with said cathode, said first

portion being fixedly mounted and said second portion being operably mounted on said first portion, one of said first member and said second portion being pivotably mounted for movement relative to the other of said first member and said second portion to allow adjustment of the angle defined between facing surfaces of said first member and said second portion; and

(c) an anode comprising a support rod having a central portion and end portions substantially perpendicular to said central portion, and a multiplicity of individual anode tips arrayed from said central portion to form at least a single row of said tips, each row defining a plane which is substantially parallel to the plane defined by said end portions, said end portions being affixed to said second portion of said anode holder, and means for maintaining a potential between said anode and said cathode, said angle being adjusted as a function of said potential.

2. The source of claim 1 further characterized in that said cathode is fixedly mounted and said second portion is pivotably mounted on said first portion thereby to define an adjustable mounting angle between said portions, and said potential is in the range of from about 7000 to about 17,000 volts and said mounting angle is in the range of from about 30° to about 50°.

3. In a mass spectrometer an improved field ionization source which comprises in combination:

- (a) an anode comprising a support rod and a multiplicity of individual anode tips affixed to said support rod and in electrical contact therewith, said tips defining at least one row;
- (b) a cathode located below said anode and having a slit which runs substantially parallel to said support rod;
- (c) said row being disposed at an angle in the range of from about 30° to about 50° from a plane drawn along the length of said slits and perpendicular to the plane of said slit; and
- (d) means for maintaining a potential field gradient between said cathode and said anode.

4. In an improved field ionization source for use in a mass spectrometer comprising in combination:

- (a) an anode holder having first and second portions, said second portion being pivotably mounted on said first portion to allow for adjustment of the mounting angle defined between said portions; and
- (b) an anode including a support means affixed to said second portion and having an outer surface, and a multiplicity of individual anode tips arrayed from said outer surface to form at least a single row of said tips, each row defining a plane which is substantially perpendicular to said outer surface.
